UNITED STATES PATENT OFFICE.

JOSHUA C. CONRAD, OF CEMENT, OKLAHOMA.

COTTON-MACHINE.

1,331,000.

Specification of Letters Patent. Patented Feb. 17, 1920.

Application filed July 27, 1918. Serial No. 247,009.

To all whom it may concern:

Be it known that I, JOSHUA C. CONRAD, a citizen of the United States, residing at Cement, county of Caddo, and State of Oklahoma, have invented certain new and useful Improvements in Cotton-Machines, of which the following is a specification.

This invention relates to cotton machines, and may be more particularly identified 10 with that class of machines which are used in the recovery of seed cotton from the hulls and other trash before feeding the seed cotton to the ginning machine.

As is well known to those more intimately 15 associated with cotton ginning and separating processes, the trash which has passed through the devices for separating the cotton from the hulls, is usually burned, or in other ways disposed of. It is also a well 20 known fact that such trash and hulls contain a material amount of seed cotton and seed, which, if it were possible to recover, would materially increase the profits of the plant. No devices, however, have been con- 25 trived whereby there may be a recovery of all valuable matters mixed in with the trash, in a manner thoroughly efficient, and yet which is sufficiently simple and cheap in construction as to be practical. It is the pri- 30 mary object of my invention to provide means by which a complete recovery may be had of all such seed cotton, fiber and seed.

A further and a particular object of my invention is to provide an improved ma- 35 chine of the character mentioned whereby the bolly cotton may be fed from the distributor to the gin and during such process of feeding may be thoroughly cleaned of trash and hulls and all the fiber removed 40 from the trash and hulls before the latter are discharged from the machine.

A further object of my invention is to provide a device for attaining the desired 45 result, which will be simple in construction, composed of but comparatively few parts, and which may be installed and operated at such low cost as to render the same practical to the ordinary cotton cleaning and ginning institution.

50 A still further object of my invention is to provide a device as thus briefly set forth, which is operated entirely by mechanical means, and which automatically separates the cotton and seed, from the shells and 55 trash, and which after the separation, de-

posits the seed cotton, seed and trash in separate receptacles.

With these objects in view, together with others which will appear as the description proceeds, my invention resides in the arrangement of rotating cylinders provided with disintegrating means, means for conveying the trash and seed cotton to the cylinders, means for bringing the trash and shells into contact with the revolving cylinders, 60 the provision of brushes or beaters co-operating with the cylinders to throw back into the conveying means any shells or matter other than seed cotton, and means for removing any seed cotton collected by the dis- 65 integrating means.

My invention further consists in the arrangement as thus briefly described, the conveying means being provided with co-operating elements for the separation of the seed 70 or trash from the shells, and a second conveyer for carrying the seed and trash to the depository provided.

My invention still further consists in the arrangement of a conveyer between a pair 75 of revolving disintegrating cylinders, rotary picks or picker rollers co-operating with the conveyer for forcing the trash and shells, carried by the conveyer, into contact with the revolving cylinders, brushes or beaters 80 co-operating with the cylinders to break and relieve from the latter any shells or trash which might have collected thereon, the arrangement being such as to deliver the trash, hulls and seed cotton to the cylinders, 85 and brushes or beaters, upon several occasions before the shells are finally discharged from the machine, means for relieving the cylinders of the collected seed cotton, and means for depositing the seed cot- 90 ton and shells into their respective depositories.

With these objects in view, together with others which will appear as the description proceeds, my invention resides in the novel 100 combination and arrangement of parts, all as will be more fully described hereafter, and particularly pointed out in the appended claims.

My invention will be more readily understood with reference to the accompanying drawings, in which—

Figure 1, is a front elevation of a cotton machine constructed in accordance with my invention,

Fig. 2, is a rear elevation of the device illustrated in Fig. 1,

Fig. 3 is an enlarged top plan view of the device, parts of which are broken away,

5 Fig. 4 is a vertical section taken substantially upon the line 4-4 of Fig. 3,

10 Fig. 5 is a vertical longitudinal section taken substantially upon the line 5-5 of Fig. 3, illustrating the general relation of the coöperating parts, and also showing a modified form of disintegrating cylinder and means for relieving the same of trash or other undesirable matter,

15 Fig. 6 is a fragmentary transverse section, illustrating the upper parts of the device, and taken upon the line 6-6 of Fig. 5, and

20 Fig. 7 is a detail view of a portion of one of the disintegrating saws illustrating the application of a rotary brush thereto.

Referring now more particularly to the drawing, 1 represents generally a frame, within which is positioned the mechanism employed in carrying out my invention, 25 and this frame comprises vertical bars or supports 2, longitudinally extending side bars 3 and transverse end bars or supports 4; the combined arrangement of which constitutes a suitable frame for the accommodation of the several mechanical parts resorted to in attaining the desired ends. Within the frame thus provided, extending longitudinally thereof, and in a horizontal plane, is a pair of cotton collecting or disintegrating cylinders or drums 5 and 6. 30 These cylinders or drums are arranged preferably at opposite sides of the frame, and preferably in the same horizontal plane, and are provided in their peripheries with oppositely disposed outwardly extending disintegrating teeth 7. As shown more clearly in Figs. 3 and 4 of the drawings, 35 these teeth are preferably stamped from the metal constituting the surface of the drums, are of substantially V-shape and bent or extended outwardly at an angle to present sharp points. It is also to be observed that these teeth are in staggered relation to each other so that upon rotation 40 of the drum, anything coming in contact with the outer surface thereof will be engaged by some of the teeth. Each of the drums is secured upon a shaft 8 which is mounted in bearings at each end upon opposite end members of the frame 1, and in 45 operation the drum or cylinders are adapted to rotate in opposite directions. Located substantially mid-way between the cylinders, in a plane slightly below the center 50 thereof, and extending in the same longitudinal direction of the shaft 8, is a conveyer 11. This conveyer, in the present instance, consists of a worm 12, mounted for rotation at one end in a suitable bearing 55 bracket 13 upon the frame, and extending 60

beyond the main frame at the opposite or rear end to be mounted in bearings 14 secured upon the structure 15 at a distance substantially remote from the frame proper of the device. The exposed end, or that portion of the conveyer worm which extends beyond the rear end of the frame, rotates in a hopper 16, which latter is provided with a perforated bottom 17, and beneath said bottom is a longitudinally extending trough 18, which extends into the main portion of the device as shown clearly in Fig. 5 of the drawings. The side walls of the hopper 16 terminate at the rear end of the frame 1, so that the conveyer worm 12 will be substantially uninclosed when within the frame proper of the device. The trough 18, which extends substantially throughout the length of the structure is preferably provided with a worm 19, 85 mounted for rotation in suitable bearings, and the convolutions of which may be such as to convey material in a direction opposite to that of the feed of the worm 12. A discharge 20 is provided at the extreme 90 rear end of the trough 18, which may extend through either the bottom, rear or side of the machine in order that the contents of said trough may be delivered therefrom.

95 When used as a gin-feeder the portion extending rearwardly from the main frame may be omitted and the bolly cotton fed directly from the distributor between the drums 5 and 6.

100 Located upon each side of the conveyer 11, between the said conveyer and the cylinders 5 and 6, and extending in the same longitudinal direction therewith, is a plurality of picker rollers 21, 22, 21^a, 21^b and 21^c. These rollers are mounted to be carried by their respective shafts 23, 24, 23^a, 23^b and 23^c, and are so positioned with relation to the conveyer that the upper circular edges thereof are slightly above the 110 level of the perforated bottom 17 of the hopper 16; a multitude of radially extending bristles or spikes being provided in the peripheries thereof. Each of these picker rollers 21 and 22 is adapted to rotate in the 115 same direction with its adjacent disintegrating cylinder or drum.

120 Within the main frame, the trough 18 is flattened somewhat, as indicated in Fig. 4, and above said trough and between the same and the rollers is a screen 18'. The rollers 21^a, 21^b and 21^c together with the screen 18', are terminated short of the front of the machine, forming a discharge passageway 16' for the trash and hulls.

125 From the foregoing description it will be seen that upon operation of the elements so far described a quantity of trash, hulls and seed cotton placed within the hopper 16 will be conveyed into the frame of the device and 130

into a position to be acted upon or treated by the disintegrating cylinders 5 and 6. It will also be obvious that during the conveying operation, any seed which may have been 5 deposited with the trash into the hopper 16 will be ejected therefrom through the perforated bottom 17 and the screen 18' into the trough 18, and conveyed to a suitable receptacle or depository by the conveyer 19. 10 During the rotation of the conveyer 12 in its conveying operation, it will also be obvious that the shells, trash, or bolly cotton, will be, to a certain degree, crushed and separated so that upon reaching a position with- 15 in the frame proper to be operated upon by the spiked rollers and cylinders, the refuse will be broken up and in better condition to be treated for the recovery of valuable mat- 20 ters therefrom. Upon entering the frame proper of the device, the contents of the conveyer will be forced into engagement with the spiked rollers 21, 22, 21^a, 21^b and 21^c and the latter, through their rapid rotation, will convey the same into a position to be con- 25 tacted by the teeth of the rotating cylinders. The teeth of these cylinders will in turn, cut or break the shells, or carry them in their rotation, upwardly to be contacted by the oppositely rotating coöperating brushes 30 or beaters 25 and 26 mounted for rotation upon their respective shafts 28 and 29 which are provided to brush or knock back into the trash conveyer all shells or other similar undesirable matter, but will not permit any 35 fibers or seed cotton to be retained by the disintegrating teeth 7. These brushes or beaters 25 and 26 are arranged preferably above the cylinders 5 and 6, being spaced therefrom a suitable distance to allow the 40 bristles thereof to extend close to the teeth to free the latter of any material which may have accumulated thereon. In this manner it will be apparent that any shells, sticks or other trash which has accumulated upon the 45 cylinders will not only be removed from the latter, but will be thrown back in the path of the conveyer to be again subjected to the treatment, and to be finally conveyed from the machine through the discharge passage- 50 way 16' at the extreme end of the trough 16. In order that the cotton separated from the bolly cotton or hulls by the teeth of the disintegrating cylinders may be removed therefrom, to be deposited in a suitable receptacle, a pair of secondary rotary brushes 55 31 and 32 is arranged, preferably beneath and extending longitudinally of the cylinders, with the bristles thereof engaging the teeth upon the rotating cylinder. The 60 brushes are each mounted upon their shafts 33 and 34 respectively, and the ends of the latter are suitably journaled in bearings 35 secured to the frame. A casing 36, inclosing substantially the entire lower portion of the 65 device, is provided, in order that the cotton

thus collected, may be delivered, through the discharge opening 37, to the gin.

In order that the shells and trash after being subjected to the treatment by the disintegrating cylinders, may be discharged 70 from the machine, a conveyer 38 is provided beneath the seed conveying trough 18, and which is in communication with the discharge passageway 16'. The conveyer 38 is inclosed by a trough-like casing 39 so that 75 the small particles of trash, after having been operated upon in the manner described to be relieved of all valuable matter will be finally deposited, through the operation of the spiked rollers, into the conveyer 38 to 80 be conducted through the discharge 38' from the machine.

In Figs. 5 and 6 of the drawings I have illustrated the general principle of my invention with modified cylinders and means 85 for relieving the same of shells or trash. In this form of my device I dispense with the cylinders as illustrated in the device above described, and substitute gangs 5' and 6' of rotary saws. These saws are 90 mounted securely upon their respective shafts and are held in spaced relation to each other by spacing blocks or disks 9 and with the exception of this particular arrangement, the operation of the saw gangs 95 is identical to that of the cylinders or drums above referred to. In order that the more solid matter collected by the saw teeth may be disengaged therefrom and returned to the conveyer, I substitute in 100 place of the brushes 25 and 26, beaters or kickers 25' and 26', which are shown more particularly in Fig. 6 of the drawings to present a plurality of outwardly extending arcuate arms. These arms are adapted in 105 operation to extend close to the saws constituting the saw gangs, to relieve the same of any shells or other similar material from the teeth of the saws.

In Fig. 7 of the drawing I have illustrated 110 a still further modified form of the device, in which the saw gangs illustrated particularly in Figs. 5 and 6 are employed in connection with the rotary brushes de- 115 scribed in the preferred form of the de- vice for relieving the cylinders of shells and other trash. When the saw gangs are substituted in this respect, it is necessary that some means be provided to prevent small particles of shells from becoming 120 mixed with the gleaned cotton, through the spaces between the several saw blades, and to obviate this objection the disks 9" are increased in diameter so that their peripheries extend nearly flush with the base 125 or root of the teeth of the saw. It will be seen from this arrangement that saw gangs may be readily substituted for the disintegrating cylinders described in the preferred form of the device without working 130

any disadvantages or inefficiencies in the operation of the machine.

The machine as thus described may be driven in any preferred manner, however, the following arrangement has been found in practice to be most efficient. Power is applied primarily to the machine through the chain 43, which imparts rotary motion through the brush shaft 33 and the gears 44 and 45 to the shaft 8 carrying the cylinders 5. The shaft 8 is extended rearwardly beyond the main frame of the device, and is provided at its extremity with a sprocket 46, through which rotary motion is imparted to the worm 12 through the chain 47 and gear 48. A sprocket 49 is provided upon the forward end of the shaft 33 by means of which the shaft 8 upon the opposite side of the machine is operated, through the medium of the sprocket chain 50 and sprocket wheel 51. The motion thus imparted to this shaft 8 is utilized to rotate its respective brush or beater gang, and spiked rollers, through the chain 52, and the sprockets 53 and 54 respectively of the said beater gang shaft and the spiked roller shafts, while the motion already imparted to the opposite shaft 8 is similarly delivered to its coöperating brush 25, and spiked roller 21 through the sprockets 55, 56 and 57, and the chain 58. Power necessary to operate the conveyer 38 is derived from the sprocket 59 upon one of the cylinder shafts; a sprocket 60 upon the shaft of the said conveyer 38 deriving its power through the sprocket chain 61. This conveyer shaft in turn imparts rotary motion to the seed conveyer 19 through the sprockets 62 and 63, and the sprocket chain 64.

It will be obvious from this description that bolly seed cotton may be treated, before going to the gin, to relieve the same of cotton seed, hulls and trash, and thus greatly hasten the ginning process. It is also obvious that by the thorough treatment of the entire body of the contents which is delivered to the device, the shells and trash may be destroyed with the least possible danger of any cotton or seed being wasted. It is also to be particularly observed that the construction set forth is of such character as to be cheap in manufacture, simple in its construction and operation, and that any of the parts which may become worn or disabled may be quickly and easily replaced at comparatively small cost. It should be understood that the devices may be used in batteries as is common practice with gin feeders, the branches of the distributor feed either to the hoppers 16 or directly between the drums 5 and 6 as above mentioned. While in the above specification I have described the device in its simplest and most concise form, it is to be understood that various minor changes

in the construction, and arrangement of the several parts, may be made without departing from the spirit and general scope of the invention.

I claim:

1. A device for removing seed cotton and seed from hulls and trash comprising conveyer, disintegrating cylinders on opposite sides of said conveyer, means for conveying the contents of said conveyer into contact with said cylinders, and means for brushing said cylinders, substantially as described.

2. A device for removing seed cotton and seed from hulls and trash comprising conveyer, cylinders on opposite sides of said conveyer, provided with disintegrating teeth, spiked rollers under said conveyer and between the same and said cylinders whereby the contents of said conveyer will be conveyed into immediate contact with said teeth, and means for cleaning said cylinders and teeth, substantially as described.

3. In a device of the class described, a conveyer, disintegrating cylinders rotatably mounted on opposite sides of said conveyer and adapted to rotate in opposite directions, spiked rollers under said conveyer and between the same and said cylinders whereby the contents of said conveyer will be conveyed into immediate contact with said cylinders, and means for brushing said cylinders, substantially as described.

4. In a device of the class described, oppositely rotating disintegrating cylinders, means for conveying refuse to said cylinders and brushes mounted to rotate at a greater speed than, and with their bristles contacting said cylinders, substantially as described.

5. In a device of the class described, oppositely rotating disintegrating cylinders, means for conveying refuse or bolly seed cotton to said cylinders and rotary brushes mounted with their bristles engaging and rotating in opposite direction to and at a greater speed than said cylinders, substantially as described.

6. In a device of the class described, a conveyer adapted to receive bolly cotton or gin refuse, means coöperating with said conveyer for separating seed cotton from said refuse or hulls, cylinders on opposite sides of said conveyer, provided with cotton collecting teeth, spiked rollers coöperating with said conveyer to convey said bolly cotton or refuse into immediate contact with said cylinders, and brushes coöperating with the teeth of said cylinders for removing fiber therefrom, substantially as described.

7. In a device of the class described, a conveyer inclosed within a trough-like receptacle, said trough-like receptacle being provided in its bottom with perforations whereby cotton seed or dirt may be discharged, a second conveyer mounted in a

trough beneath said first conveyer for carrying the discharged seed or dirt to a depository, cylinders on opposite sides of said first conveyer, provided with cotton collecting 5 teeth, spiked rollers coöperating with said conveyer whereby the contents of said conveyer will be brought into contact with said cylinders, and brushes for removing any matter secured to the teeth of said saws, 10 substantially as described.

8. In a device of the class described, a conveyer inclosed within a perforated trough-like receptacle, a second conveyer beneath said trough-like receptacle, gang saws 15 on opposite sides of said first conveyer and spiked rollers between and under said saws and said conveyer whereby shells carried by the latter will be brought into contact with the said saws, a receptacle provided

with a conveyer beneath and coöperating 20 with said spiked rollers whereby said shells will be removed from the machine, rotary brushes coöperating with said saws to remove any matter collected upon the teeth thereof, and a receptacle for the matter thus 25 removed, substantially as described.

9. A device as set forth in claim 3 further characterized by a screen beneath the spiked rollers under the conveyer, substantially as described. 30

In testimony whereof I have signed my name to this specification in the presence of two subscribing witnesses.

JOSHUA C. CONRAD.
